HOOK SUPPORT FOR CARRIER BAG HANDLE

Seymour Kamins, Oceanside, and Norman Rosenberg,
Bayside, N.Y., assignors to CTP Industries Inc., Brooklyn,
N.Y., a corporation of New York

Filed Oct. 9, 1968, Ser. No. 13,910

Term of patent 14 years

Int. Cl. D9—99

U.S. Cl. D9—291

FIG. 1.

FIG. 2.

FIG. 1 is a perspective view of a hook support for a carrier bag handle showing our new design; and FIG. 2 is a side elevational view thereof.

The fragmentary broken line representation of a carrier bag in FIG. 1 is for purposes of illustration only.

I claim:

The ornamental design for a hook support for carrier bag handle, as shown and described.
